UNITED STATES PATENT OFFICE

94,118

DESIGN FOR A FOUNTAIN PEN OR SIMILAR ARTICLE

Seth Chilton Crocker, Boston, Mass.

Application July 5, 1934, Serial No. 52,460

Term of patent 3½ years

To all whom it may concern:

Be it known that I, Seth Chilton Crocker, a citizen of the United States, residing at Boston, in the county of Suffolk and State of Massachusetts, have invented a new, original, and ornamental Design for a Fountain Pen or Similar Article, of which the following is a specification, reference being had to the accompanying drawing, forming part thereof, in which:

Fig. 1 is a view in side elevation and
Fig. 2 is a cross sectional view at line 2—2 of
Fig. 1, showing my new design.

I claim:

The ornamental design for a fountain pen or similar article, as shown.

In testimony whereof, I have signed my name
to this specification.
